UNITED STATES PATENT OFFICE.

GEORGE W. BERRY, OF ROSE BAY, NEAR SYDNEY, NEW SOUTH WALES, AUSTRALIA,
ASSIGNOR TO THE WIRELESS HINGE MANUFACTURING COMPANY LIMITED, OF
SYDNEY, AUSTRALIA.

APPARATUS FOR AUTOMATICALLY FORMING AND CONNECTING HINGE MEMBERS ON THE LIDS AND BODIES OF SHEET-METAL RECEPTACLES.

1,311,587.

Specification of Letters Patent. Patented July 29, 1919.

Application filed February 15, 1917. Serial No. 143,767.

To all whom it may concern:

Be it known that I, GEORGE WILLIAM BERRY, a subject of the King of Great Britain, residing in Rose Bay, near Sydney, in the State of New South Wales, Commonwealth of Australia, engineer, have invented new and useful Improvements in Apparatus for Automatically Forming and Connecting Hinge Members on the Lids and Bodies of Sheet-Metal Receptacles, of which the following is a specification.

This invention has been devised in order to provide improvements in and connected with sheet metal presses for forming hinge members on and hingedly connecting the lids and bodies of sheet metal receptacles having one or more flat sides in a simple and efficient manner.

The invention relates particularly to a sheet metal press that is furnished with three sets of dies for simultaneously treating receptacles and lids and with means whereby the lid and body blanks are progressively and intermittently passed from one set of dies to another to form the hinge members and connect the lids and bodies in three successive operations.

Improvements embodied in the present invention comprise firstly, novel means for insuring a correct feeding of the lid and body blanks to their respective dies; secondly, means for conveying the lids and bodies progressively and intermittently from one set of dies to another; thirdly, means for pushing the lids and bodies on to the dies and for returning them to their respective conveying devices after being operated on by the said dies; fourthly, means for hingedly connecting the lids and bodies on which have been formed hinge-members; fifthly, means for discharging the hingedly connected lids and bodies from the machine; sixthly, the general construction and arrangement of the operative parts whereby access can be conveniently had to the same for adjustment, renewal or repairs.

The machine is particularly adaptable for securing the lids to tins in which tobacco, confectionery, medicinal and chemical preparations and other goods are commonly packed for sale or transport.

In order that the invention may be readily understood reference will now be had to the

accompanying sheets of explanatory drawings, wherein—

55

Figure 1 is a view in perspective of a press constructed in accordance with the invention the constructional features for feeding, forming hinge members and discharging the hingedly connected lids and bodies being omitted for convenience of illustration.

Fig. 24 is a view in perspective showing the means employed to close the lids on the bodies and discharge the same from the press.

Figs. 25 and 26 are views in sectional side elevation taken on the planes A—A and B—B respectively of Fig. 24.

Fig. 27 is a view in perspective of a constructional modification in part of the apparatus shown in Fig. 24.

Figs. 28 and 29 are views in perspective of body and lid blanks respectively.

Fig. 30 is a view in sectional side elevation of portions of the first hinge forming die, portions of a lid and body blank being shown in section thereon.

Fig. 31 is a view similar to Fig. 30 showing the die closed on the lid and body blanks.

Figs. 32 and 33 are views in perspective of body and lid blanks as shaped by the first die.

Fig. 34 is a view in sectional side elevation showing the second hinge forming die in its open position, portions of the lid and body, as shaped by the first die, being shown in position thereon.

Fig. 35 is a view similar to Fig. 34 showing the die closed on the lid and body.

Figs. 36 and 37 are views in perspective showing portions of the lid and body, respectively, as shaped by the second die operation.

Fig. 38 is a view in sectional side elevation of the third die shown in its open position with the lid and body in position to be connected thereby.

Fig. 39 is a view similar to Fig. 38 showing the third die closed on the hinging members of the lid and body.

Fig. 40 is a view in perspective of a lid and body hingedly connected by means of the invention.

Fig. 41 is a perspective view of the first set of dies for performing the operations indicated in Figs. 30 and 31.

Fig. 42 is a similar view of the second set of dies used for performing the operations indicated in Figs. 34 and 35.

Fig. 43 is a similar view of the die members for performing the operation shown in Figs. 38 and 39.

Fig. 44 is a rear side view of one member of the top die shown in Fig. 42.

65 In Figs. 41, 42 and 43 the top die is tilted

over to expose its under face to facilitate description thereof.

Fig. 45 is a view in sectional side elevation of a modified form of device for feeding the lid blanks to the press.

Figs. 46 and 47 are views in sectional side elevation and sectional plan respectively of part of Fig. 41 taken on the dotted lines 10—10 and 11—11.

Fig. 48 is a view showing a modification 75 of that part of the invention illustrated in Figs. 9 and 22 and hereinafter will be fully described.

Referring to the drawings wherein like characters of reference have been employed 80 to indicate similar or corresponding parts of the different views the numeral 20 designates a cast metal frame the lower part of which is not shown and can be given any approved design. The upper end of the 85 frame 20 is provided with two bearings 21 in which is revolubly mounted a driving shaft 22 furnished at its rear end with a combined belt and fly wheel 23.

A crank 24 is fitted to or formed integrally on the front end of the driving shaft 22 and the motion of said crank is adapted to impart a vertical reciprocatory movement to a cross-head 25. The cross-head 25 is connected to the crank 24 by means of a link 26 95 and the said cross-head is designed to slide freely in vertical guides 27 formed on or fitted to the head of the frame.

The underside of the cross-head 25 is fitted with a die-head 28 having bosses 29 adapted 100 to move freely over vertically disposed guide pillars 30 fitted to a movable die base 31.

Fitted to the underside of the die head 28 are three top dies 32, 33 and 34 that are adapted to move to and from and register 105 with a similar number of bottom dies 32', 33' and 34', respectively, fitted to the movable die base 31. The die head 28 is formed with a depending portion 35 that extends transversely across the center and underside 110 thereof and passing through the said portion are three parallelly arranged recesses 36 that are located above the three bottom dies. The

recesses 36 are designed to accommodate shanks 37 formed on or fitted adjustably to 115 the top dies. The top dies are connected to the shanks 37 by means of stud bolts and enlarged holes 38, as shown in dotted lines in Fig. 4 of the drawings. An inverted T-shaped channel 39 is formed in the upper ends of each of the shanks 37 to accommodate the shaped ends of adjustment screws 40 that pass downwardly through the die head 28. The adjustment screws 40 have shaped heads to permit of them being operated to raise or lower the die blocks as required and the said screws are furnished with lock nuts 41 by means of which they can be held fixedly in any adjusted position.

The shanks 37 are of slightly greater width 130

than the depending portion 35 and they are retained firmly in their correct positions within the recesses 36 by means of plates 42 and stud bolts 43. The stud bolts 43 are 5 screwed tightly into the depending portion 35 and project forwardly and rearwardly to pass through holes in the clamping plates 42. The clamping plates 42 are forced against the front and rear faces of the shanks 37 by 10 means of nuts 44 on the stud bolts 43 and the front plate can be made in sections to permit of the independent removal of the top dies, see Fig. 4.

The bottom dies 32', 33' and 34' are 15 cured to die blocks 45 by means of set-screws 46 that pass downwardly and screw into the top of the movable die base 31.

The lid and body blanks 47 and 48 (see 20 Figs. 28 and 29) to be hingedly connected are fed to the right hand side of the machine through chutes 49 and 50, respectively, and are directed to the bottom dies by the 25 intermittent operation of push rods 51 reciprocatingly mounted in channels 52 formed transversely in the top of the movable die base.

The lids and bodies are fed to the upper 30 ends of the feed chutes 49 and 50 and provision is made to insure the said lids and bodies passing correctly down the same to stepped platforms 53 fitted to the push rods 51. The upper ends of the feed chutes 49 and 50 curve gradually downward toward each other and their lower ends are arranged 35 vertically and are fitted detachably to a clamping frame 54 that fits in a guide frame 55 bolted to a lateral extension 56 of the movable die base.

The lower ends of the feed chutes 49 and 40 50 fit snugly in the clamping frame 54 and the said frame is secured firmly in a recess 57 formed in the top of the guide frame by a set screw 58.

The set-screw 58 is fitted to a boss formed 45 on the upper end of a disappearing bracket 59 pivoted loosely on a pin 60 supported between lugs 61 formed on the guide frame 55. The set-screw is locked in its set position by a thumb-nut 62, see Fig. 5.

50 The guide frame 55 is fitted with parallelly disposed fences 63 that are arranged along the sides of each of the push rods 51 and insure the lids and bodies being kept in their correct positions when they fall on to 55 the stepped platforms 53 from the feed chutes and while being conveyed to the first bottom die 32'. The fences are supported at one end on the guide frame 55 and by a bridge piece 64 fitted to an inward extension 60 of said guide frame.

The outward movements of the push rods cause the lids and bodies to be moved progressively forward down steps 65, 66 and 67 to the level of the said rods. The lids and 65 bodies fall from the feed chutes on to the

uppermost step 65 of the platforms 53 and the inner side of the guide frame 55 is cut away at 68 to provide sufficient clearance for the lids and bodies to pass freely toward the dies when the push rods are thrust inwardly, 70 see Figs. 16 and 17. The outer side of the guide frame 55 is cut away to permit of the free operation of the push rods 51. When the push rods 51 move to their outermost position—as shown in Fig. 16—the lowermost lid and body in the chutes 49 and 50 fall from the uppermost steps 65 upon the steps 66. The “rises” 69 of the steps 65 bear against the outer ends of the lid and body resting on the steps 66 when the push rods 51 commence their inward stroke, and when the said push rods have completed their stroke the lids and bodies are situated in advance of spring pawls 70. The spring pawls 70 are made of flat spring metal and their outer ends are fitted to the sides of the fences 63 and their inner ends pass through slots 71 to the inside of the fences. The inner ends of the spring pawls 70 are forced outwardly by the lids and bodies passing 90 between the fences and when the said lids and bodies are moved past the said pawls the latter move inwardly behind the former and prevent them moving outwardly with the return stroke of the push rods. When the 95 push rods have completed their second outward stroke the lid and body resting on the steps 66 pass over the “rises” 69 of said steps and fall upon the steps 67. The rises 69 of the steps 66 lie against the outer edges 100 of the lids and bodies and the next inward stroke of the push rods causes the said lid and body to be moved in advance of a second pair of pawls 70 fitted to the sides of the fences as above described.

The next outward stroke of the push rods 105 51 causes the steps 67 to be withdrawn from beneath the lid and body which then fall upon wearing strips 72 that are fitted to the movable die base 31 on the inside of said push rods. The rises of the steps 67 bear upon the outer ends of the lid and body on the next inward stroke of the push rods and when the said rods have reached the limit of their stroke the lid and body are placed 110 directly opposite the rear and front, respectively, of the first bottom die 32'. Each successive operation of the push rods 51 will now place a lid and body at the rear and front, respectively, of the bottom die 32'. 115

The bottom of the channels 52 in the movable die base for accommodating the push rods 51 is provided with wearing strips 73.

The outer ends of the push rods 51 are arranged to move between adjustable guide 125 strips 74, that can be adjusted by means of set-screws 75, fitted to the lateral extension 56 and guide frame 55, see Figs. 4 and 5 of the drawings.

The outer ends of the push rods are pro- 130

vided with screw threaded extensions 76 that are connected by a cross piece 77. The said cross-piece is securely fastened to the screw threaded extensions 76 by nuts 78 and by 5 altering the positions of the said nuts the push rods can be adjusted independently as required.

A jaw 79 is formed on the cross-piece 77 and pivotally mounted in said jaw is one 10 one end of a link 80 the opposite end of which is pivotally mounted on a pin 81 carried by an upwardly projecting arm of a rocking lever 82. The rocking lever 82 is pivotally mounted on a pin 83 that is supported by bearings 84 on the lateral extension 56 of the movable die base.

The end of lever 82 depending below the pivot pin 83 is bifurcated and fitted with a roller 85 that is arranged to bear on a cam 20 86 fitted slidably on a shaft 87 mounted revolvably in bearings 88 fitted to the right-hand side of the frame 20. The rear end of the shaft 87 is fitted with a gear wheel 89 that meshes with a like wheel 90 fitted to the 25 lower end of an inclined shaft 91 mounted revolvably in bearings 92 in the frame 20. The upper end of the inclined shaft 91 is fitted with a gear wheel 93 that meshes with a gear wheel 94 fitted to the driving shaft 30 22 between the bearings 21 for the same.

The push rods 51 are actuated by the lever 82 and cam 86 and the said cam is constructed in such a way that the said push rods will have an idle period when at the 35 ends of their stroke. The lever 82 is fitted with a spring 95 that is arranged to exert a pressure that will insure the roller 85 always bearing against the cam 86 and said spring also insures a regular and positive movement 40 being imparted to the push rods.

When the upper end of the lever 82 moves to its outermost position it abuts against the point of a set-screw 96 screwed into the lateral extension 56. The purpose of the set-screw 45 96 is to prevent the lever moving outwardly beyond a correctly determined position.

When a lid and body have been advanced to a position opposite the first bottom die 32' 50 they are thrust over the back and front, respectively, thereof by push pads 97 that are carried on bars 98 reciprocatingly mounted on the movable die base 31. The push pads conform more or less to the shape of the 55 lid and body and are fitted with stems 99 that are reciprocatingly mounted in holes 100 formed in the bars 98. The ends of the stems 99 are provided with reduced screwed extensions 101 that pass through the bars 60 98 and are fitted with nuts 102.

Compression springs 103 encircle the reduced extensions 101 and are arranged to keep an outward pressure on the said push pads 97. By adjusting the nuts 102 on the 65 extensions 101 the push pads can be made

to project more or less in advance of the bar 98 under normal conditions. The springs 103 insure a resilient pressure between the push pads and the backs of the lids and bodies when being thrust on to 70 the dies. The resilient pressure exerted by the springs 103 holds the lids and bodies frictionally against the dies in such a way that the said lids and bodies can be forced slightly downward, when the top dies 75 descend, without distorting or causing injury to the same. The backs of the push pads 97 are fitted with guide pins 104 that fit slidably in holes formed in the bars 98 and prevent rotation or any rocking movement 80 of said pads.

The top dies are timed to operate when the lids and bodies have been thrust correctly on to the bottom dies.

The bar 98 operating in the front of the 85 machine carries three push pads 97 that are located directly in front of the three bottom dies 32', 33' and 34' and the ends of the said bar are fitted with two forwardly projecting guide pins 105 that are arranged to 90 slide freely in long bosses 106 formed on brackets 107 fitted to the front of the movable die base.

The bar 98 operating in the rear of the 95 press carries two push pads 97 that are located directly behind the two first bottom dies 32' and 33' and the ends of this said bar 98 are fitted with two rearwardly projecting guide pins 105 that are arranged to slide freely in long bosses 106 formed on 100 brackets 107 fitted to the rear of the movable die base.

The front bar 98 is provided with forwardly projecting jaws 108 and the rear bar 98 is formed with rearwardly projecting 105 jaws 109 and these jaws 108 and 109 are connected by links 110 to the upper ends of levers 111 and 112 that are mounted on the front and rear, respectively, of the movable die base.

The lever 112 for operating the bar 98 at the rear of the bottom dies is fulcrumed on a pin 113 carried in bearings 114 fitted to the rear of the movable die base. The pin 113 is located at about one-third of the 115 height of the lever 112 from its upper end. A roller 115 is mounted near the lower end of said lever and arranged to bear against a cam 116 that is fitted to a transverse shaft 117 mounted in bearings 118 fitted to the 120 rear of the movable die base. The right hand end of the shaft 117 is fitted with a gear wheel 119 that meshes with a gear wheel 120 fitted to the shaft 87 on the right hand side of the machine frame 20.

The gear wheel 120 is connected by a sleeve 121 to the cam 86 for operating the lever connected to the push rods 51 and said sleeve is provided with flanges 122 that are located on both sides of a bearing 123 formed on the 130

end of the lateral extension 56 of the movable die base. The bearing 123 insures the gear wheel 120 and the cam 86 moving in unison with the movable base when the same is moved inwardly or outwardly on the main frame, thereby maintaining the gears in mesh. The gear wheel 120 and cam 86 are arranged to slide on a feather 124 fitted to or formed on the shaft 87 and this feather 10 prevents any independent rotation of the said gear wheel or cam.

One end of a connecting rod 125 is pivoted to a pin 126 on the lever 112 at a point between the fulcrum pin 113 and the roller 15 115 and the opposite end of the said connecting rod 125 passes through a block 127 pivotally mounted on the lever 111 for operating the front bar 98. The block 127 is located about one-third of the length of the 20 lever 111 from its upper end and the lower end of said lever is pivoted in a jaw 128 on the front of the movable die base.

The end of the connecting rod 125 passing through the block 127 is fitted with a compression spring 129 one end of which bears against said block and the opposite end against lock-nuts 130 fitted to the end of the said rod.

The forward end of the rod 125 is fitted 30 with nuts 131 that are arranged to bear against the inner face of the block 127 and press the upper end of the lever 111 outwardly when the lower end of the lever 112 moves inwardly.

35 The spring 129 together with the springs 103 on the stems of the push pads 97 provide sufficient resiliency to prevent breakage of the operative parts should anything fall between the push pads and the bottom dies 40 or the parts connected therewith become jammed through any cause.

The lower end of the lever 112 is fitted with a tension spring 132 the opposite end of which is connected to a bracket 133 fitted 45 to the front of the movable die base. The said spring 132 is sufficiently strong to insure the roller 115 bearing continuously against the cam 116 and so prevents knocking or irregular movement of the parts.

50 The back rim of the lid blank 47 is formed with notches 134 and between said notches the rim is formed with a depending portion 135 (hereinafter called the pintle margin) to provide stock for the formation of hinge 55 pintles.

The front of the bottom die 32' is provided with two protuberances 136 and a countersink 137 and the front of the top die 32 is formed with countersinks 138 and a depressing piece 139. The countersinks 138 and depressing piece 139 form counterparts of the protuberances 136 and countersink 137, respectively and when the top die descends on to the bottom die the protuberances 136 form 60 outwardly disposed bulbs 140 on the body 65

and the depressing piece 139 forms an inwardly disposed depression 141 between the bulbs. The protuberances 136 and countersinks 137 are shaped to make a vertical incision 142 at the inner ends of the bulbs 140 70 (see Fig. 32).

The rear of the bottom die 32' is formed with a longitudinally disposed rib 143 of the same length as or slightly longer than the pintle margin 135 of the lid rim. The top 75 die 32 is formed with two parallelly disposed drawings ribs 144 and 145 with an intervening groove 146 that is counterpart of the rib 143.

The rib 145 is slightly deeper than the rib 80 144 and as the top die descends the said rib 145 bends the edge part of the pintle margin 135 of the lid rim over the inner edge of the rib 143 before the rib 144 bears on the inner part of the pintle margin of the lid. The 85 bending and pinching of the edge of the pintle margin insures accurate drawing and bending to form a semi-tubulous edge 147 (see Fig. 33).

The bottom die blocks are cut away at 90 their lowermost parts to provide room for the front rims of the lids and bodies and for horizontally disposed platforms 148 that are actuated to lift slightly and raise the said lids and bodies clear of the forming 95 members on the bottom dies when the top dies are in the act of rising. The platforms 148 are located beneath the rear and front sides of the first and second die blocks and are depressibly mounted in channels 149 100 formed transversely in the top of the movable die base. The platforms 148 are provided with depending stems 150 that are adjustably secured by nuts 151 to a cross head 152. The platforms 148, normally, are level 105 with the wearing strips 72 and support the lids and bodies while the same are being thrust by the push pads on to the dies.

The cross head 152 is securely fastened by nuts 153 to a vertically disposed rod 154 110 which has its upper end reciprocatingly mounted in a bushing 155 in the top of the movable die base. The lower end of the rod 154 is reciprocatingly mounted in a bushing 156 in the lower part of the movable die base and a compression spring 157 encircles said rod and tends to keep a constant upward pressure on the same. The lower end of the spring 157 rests on the bushing 156 and its upper end bears against nuts 158 that 115 can be adjusted on the rod 154 to increase or diminish the pressure exerted by the said spring.

A boss 159 is fitted vertically to the underside of the die head 28 and fitted adjustably within said boss is a rod 160 that is designed to bear upon the upper end of the rod 154 just prior to the top dies meeting with the bottom dies. The object of the rod 160 is to depress the rod 154 and plat- 125 130

forms 148 before the dies commence to meet on the backs of the lids and bodies.

When the platforms 148 are depressed the fronts of the lids and bodies are left in suspension in the recesses near the bottom of the die blocks. The object in suspending the fronts of the lids and bodies as above described is to prevent them being distorted when the top dies descend.

10 The front corner of the third bottom die is rounded off to permit of the edge of the body rim passing easily thereover and rising slightly to leave the front of the said body rim suspended within the recess at the 15 base of the said die block. The rod 160 can be adjusted in length by loosening a locking nut 161 and screwing the rod farther into or out of the boss 159 as required.

When the top dies commence to rise after 20 shaping the backs of the lid and body as before described the rod 160 rises from the rod 154 thereby permitting the platforms 148 to rise to their normal positions and permit the lid and body to clear the forming members on the bottom die.

When the lid and body are raised clear 25 of the forming members of the bottom die 32' they are moved outwardly by curved ejector arms 162 and placed in advance of fingers 163 on the push rods 51.

30 The outer ends of the curved ejector arms 162 are adjustably secured by means of slots 164 and set screws 165 to the bars 98 and their inner ends curve downwardly and lie 35 between the bottom dies. The inner ends of the ejector arms 162 are provided with plates 166 that are adapted to move in recesses 167 formed in the sides of the die blocks 45. When the bars 98 move away 40 from the bottom dies the plates 166 on the ejector arms 162 bear against the edges of the lids and bodies and remove the same from the said dies.

45 The plates 166 on the ejector arms together with the front and rear faces of the die blocks 45 form one side of a guideway 168 for guiding the lids and bodies from one bottom die to another. The opposite sides of the guide-ways 168 are formed by 50 fences 169 that are bolted or otherwise secured to the top of the movable die base. The tops of the fences 169 are made to slightly overhang the guideways 168 and apertures 170 are formed therein to permit 55 of the free operation of the push pads 97. The overhanging portions of the fences 169 may be made removable to permit of the lids and bodies being conveniently removed from any point in the lengths of the said 60 guideways.

65 When a lid and body 47 and 48, respectively, have been removed from the first bottom die 32' they are carried along the guideways 168 to the second bottom die 33' by the fingers 163 on the next inward stroke of

the push rods 51. The lid and body are thrust on to the second bottom die 33' by the push pads 97 operating in front and rear thereof.

The front part of the bottom die 33' is 70 formed with two angular shaped cutters 171 that are located beneath the bulbs formed on the back of the body. The top die 33 is formed with rectangular recesses 172 that are arranged to align with the cutters 171 75 and slit the rim of the body along the upper sides and downward slightly beyond the outer ends of the bulbs 140.

The rectangular pieces of metal bounded by the slits so made are pressed outwardly 80 from the back of the body 48 in the closing of the dies forming bulbed tongues 173 (see Fig. 36 of the drawings).

A recess 174 is formed in the face of the die 33' to accommodate the depressed portion 141 on the back of the body.

The rear face of the bottom die 33' is formed with two mortises 175 that are located beneath the back of the lid rim at the inner ends of the notches 134. The top die 90 33 is formed with two depending punches 176 that are arranged in alignment with the mortises 175 and when the top die 33 descends the punches slot out portions 177 of the lid as shown by the dotted lines in Fig. 95 33 of the drawings. The slotting out of the portions 177 extends the notches 134 as shown in Fig. 37 thus forming the ends of the semi-tubulous portion 147 into hinge 100 pintles 178 that are adapted to be engaged by and pivot in the bulbs 140 on the backs of the bodies 48.

The pieces of the lid rim cut out by the punches 170 pass downwardly through the mortises 175 to discharge chutes 179 that 105 direct the pieces of material through the machine clear of the operative parts thereof.

The rear side of the top die 33 is fitted with a spring controlled stripper saddle 180 shaped to accommodate the punches 176. A 110 recess 181 formed in the stripper saddle 180 accommodates the central portion of the semi-tubulous portion 147 on the back of the lid.

When the portions 177 have been removed and the bulbed tongues 173 have been raised as shown in Figs. 35 and 36, the top die 33 is raised and the body and lid are moved outwardly from the bottom die 33' into the guideways 168 by the ejector 120 arms 162.

The body and lid shaped by the second die are then moved opposite the front and back respectively of the third bottom die 34' by the next inward stroke of the push rods 51. 125

The third bottom die 34' is narrower than the dies 32' and 33' and is shaped vertically on its front side and its rear side is inclined downwardly as shown in Fig. 9 of the drawings.

The body is thrust on to the front of the bottom die 34' by a push pad 97 arranged and operating as before described. As the lid is carried forward opposite the rear of the third die 34' it is placed in a holder 182 that is mounted on a stem 183 resiliently supported in a boss 184 formed on an angle shaped pivoted arm 185.

The stem 183 is adjustably mounted within the boss 184 in the same way that the stems 99 are mounted in the holes 100 of the bars 98. The angle shaped arm 185 is pivoted on a pin 186 that is supported in the movable die base and a roller 187 is fitted to the elbow of said arm and arranged to bear on a cam 188 fitted to the shaft 117 passing transversely across the rear of the movable die base 31. The roller 187 is kept bearing on the cam 188 by means of a spring 189 one end of which is secured to said arm below the pivot point thereof and the opposite end to a screw bolt 190 fitted adjustably to the front of the movable die base 31.

A forward extension 191 is formed on the pivoted end of the arm 185 and pivotally mounted on said extension is the lower end of a vertically disposed push rod 192, which passes through a hole 193 in the third die block and normally projects above the rear of the third die 34'.

The lid 47 fits neatly between flanges 194 on the top and bottom of the holder 182 and is retained therein by a spring controlled arm 195 having a cross-piece 196 that bears against the edges of the lid rim when the said holder is swung forwardly by the operation of the cam 188.

The arm 195 carrying the cross piece 196 is secured to a block 197 that is pivotally mounted on the pin 186 carrying the curved arm 185. The block 197 is formed with a depending lug 198 to which is attached one end of a spring 199 the opposite end being secured in a like manner to the spring 189 on the arm 185.

The top of the die base 31 is formed with a slot 31' in which the arm 195 is free to oscillate and the rear end of the said slot forms a stop for retaining the arm in its normal position. When the arm 195 is bearing against the rear end of the slot 31' the cross-piece 196 is in line with the inner side of the guideway 168.

The pin 186 supporting the angle shaped arm 185 is formed with a longitudinal bore 200 and radial holes 201 that permit the bearings of the arms 185 and 195 to be lubricated from an oil cap fitted to the outer end of said pin.

A guide plate 202 is located on each side of the third bottom die 34' and the ends of the cross-piece 196 fitted to the spring controlled arm 195 are arranged to move in recesses 203 formed in said guide plates. The guide plates 202 provide correct lateral lo-

cation and insure the pintles 178 being placed correctly beneath the bulbed tongues 173 on the back of the body when carried forward in the holder 182.

The body 48 is quite home on the bottom die 34' before the arm 185 has been moved forwardly to the limit of its travel by the operation of the cam 188 and when the said arm is completing its travel the pintles 178 are directed beneath the bulbed tongues 173 on the body.

When the top die 34 descends it closes the bulbed tongues 173 neatly over the pintles 178 on the back of the rim lid. The top die 34 is formed in two parts, one part 204 being fixed and the other part 205 being slideable against backing springs 206. The sliding part 205 normally projects below the fixed part 204 and as the die descends the two parts 204 and 205 are brought to bear one on each side of the bulbous parts of the raised tongues 173 and set the said tongues back into their original positions, now inclosing the pintles 178.

The contiguous lower corners of the two parts of the top die 34 are corner fluted as at 207 to permit of the die coming hard home without injuring the bulbs 140, the semi-tubulous portion 147 of the lid rim, or the pintles 178. The face of the bottom die 34' is formed with recesses 208 shaped to receive the edges of the pintles.

When the top die 34 recedes the lid holder 182 commences to move outwardly and the free end of the lid is held frictionally between the said holder and the cross-piece 196 on the spring controlled arm 195. The body is removed from the bottom die 34' simultaneously with the outward movement of the lid holder 182 by the action of curved ejector arm 162 fitted to the left hand end of the bar 98 carrying the push pads for the bodies 48.

When the lid holder 182 has almost returned to its normal position and the lid is released therefrom the push rod 192 is forced upwardly and bears against the inside of the lid to lift it clear of the bottom die. In order to prevent the rim of the lid fouling the push rod 192 before the same has returned to its normal position and when the hinged lid and body are being moved along from the back of the bottom die 34' an inclined bracket 209 is fitted to the outer guide plate 202. The inclined bracket 209 is placed in the path of the lid and raises it above the push rod 192 as shown in Fig. 22 of the drawings.

In order to compensate for wear on the parts and to insure the lid holder 182 being placed in accurate alinement with the guideway 168 for guiding the lids an adjustable stop pin 210 is screwed into a bracket 211 fitted to the rear of the die base. A lug 212 is formed on the boss 184 and this said lug is adapted to rest against the adjustable stop 130

pin when the arm 185 is returned to its normal position, see Figs. 2 and 10 of the drawings.

The hingedly connected lid and body are passed from the bottom dies 34' by means of the outermost finger 163 on the push rod 51 for intermittently moving the bodies through the press and when passed from said die the lid is projecting approximately horizontally from the back of the body.

The guideway 168 for the bodies is arranged in alignment with a discharge chute 213 into which the hinged lid and body are thrust by the next oncoming hinged lid and body. The discharge chute 213 can be arranged horizontally or it may incline at any required angle from the left hand side of the machine.

The front side of the entrance to the chute 213 is vertical and the rear side of the entrance is turned up to the horizontal to permit of the lid on the body passing freely into the same. The rear side of the chute 213 near the entrance passes in a gradual curve downwardly to the vertical and as the lid is forced to bear on the downwardly inclined side it is closed neatly on the body (see Figs. 24 and 25 of the drawings).

The closed lid and body passes along the chute 213 on its side until it reaches a tilting chamber 214 where its forward end strikes against an abutment 215 that causes it to tilt over on its lid side. The closed lid and body are kept in alignment with the chute 213 until the whole of it is within the tilting chamber 214 by a guide flange 216 and the back of the said chute near the tilting chamber inclines outwardly as at 217 (see Figs. 24 and 26 of the drawings).

40 The discharge chute 213 is arranged horizontally after passing from the tilting chamber 214 and the closed lid and body are directed into and along the horizontal part of the chute by the next oncoming lid and body.

45 A slot 218 of slightly lesser width than one half the width of the body is made across the bottom of the horizontal part of the discharge chute near the tilting chamber and connecting with the ends of said slot 218 are 50 gaps 219 that pass longitudinally toward the tilting chamber.

When the third die fails to connect a lid to a body the body is directed into the discharge chute 213 and when it reaches the slot 218 its forward edge falls therethrough and its side edges fall into the gaps 219 and the whole of the body gravitates or is passed through the said slot 218 by the pressure of the next oncoming body.

60 If preferred, the discharge chute 213 can be made without the tilting chamber and the horizontal portion and in this case the slot 218 and gaps 219 are made in the back of the chute. In this latter construction the body is pressed toward the slot 218 by a flat

spring 220 that is fitted to the side of the chute and passes through an opening 221 formed in the front thereof (see Fig. 27 of the drawings).

The discharge chute can be of any desired length and be given any suitable curve that will permit of it delivering the closed lids and bodies to any convenient position for packing or the like.

Those lids that fail to connect with the bodies are returned to their guideway 168 by the holder 182 and are directed from the left hand side of the machine by the next oncoming lid.

The push rods 51 are timed to move outwardly when the lids and bodies have been thrust on the dies 32', 33' and 34' by the push pads 97 carried on the reciprocating bars 98 thereby permitting the fingers 163 to pass freely in front of the bodies and at the rear of the lids. The push rods 51 commence their return stroke immediately the lids and bodies have been returned to their respective guideways 168 by the outward movement of the bars 98 and curved ejector arms 162.

It will be obvious that at each inward stroke of the push rods 51 a lid and body will be fed into the machine and that after the die head has made three downward strokes a hinged lid and body will be discharged from the machine.

The die head 28 is secured to the cross-head 25 by means of bolts 222 that pass downwardly through open slots 223 formed in the front of the said cross-head and screw into the said die head, as shown in Fig. 1.

The movable die base 31 is secured to the main frame by bolts 224 that pass through slots 225 in the bottom of said movable base and into the machine frame. The lower ends of the bolts 224 are fitted with nuts 226 that are made accessible by means of recesses 227 formed in the sides of the main frame.

A rack 228 is fitted to the underside of the movable die base 31 and the teeth of said rack mesh with a pinion 229 fitted to a shaft 230 mounted transversely in the main frame. The left hand end of the shaft 230 projects beyond the main frame and is squared to take a crank handle 231 for operating the same.

In order to free the lower ends of the feed chutes 49 and 50 so that the die base 31 can be moved outwardly the set screw 58 is loosened and the disappearing bracket 59 is raised to the limit of the slot 232 formed therein and then swung rearwardly on the pivot pin 60.

The movable die base 31 is adapted to move in guides 233 formed on the main frame and to move the said die base 31 forward or rearward the bolts 224, and nuts 226 are loosened and the handle 231 operated in the direction required. When the

handle 231 is operated the slots 223 in the cross-head 25 and the slots 225 in the said movable die base permit a free forward movement of the said movable die base to a point that will enable free access to be had to the operative parts mounted on the said base for adjustment or renewal of the same. The mechanism carried on the movable die base can be operated when the said die base is in its outermost position thereby permitting a close inspection of the operation of said mechanism. The movable die base 31 can be returned to its correct working position by operating the handle 231 in the reverse direction and it can then be clamped securely in position by tightening up the bolts 222, nuts 226 and set-screw 58 after readjusting the disappearing bracket 59.

The die-head can be supported in a raised position above the die base 31 by any approved means when said base is moved forwardly.

If preferred the movable die base 31 can be moved in and out on the machine frame by a screw 234 that is engaged by a nut 235 fitted to the said base 31. In this instance the screw 234 is carried in bearings (not shown) fitted to the machine frame and is actuated in the same manner as an ordinary vise screw.

The gearing on the shaft 87 located horizontally on the right hand side of the machine is protected by a shield 236 that is detachably secured to the lateral extension 56 of the movable die base in an approved way.

The lower ends of the feed chutes 49 and 50 are provided with means for cutting off the lids and bodies passing therethrough as and when required. In order to accomplish the above-mentioned object the rocking lever 82 is provided with a broad upper end 237 arranged with its flat sides facing the front and back of the machine and having upwardly projecting lugs 238 and 239 on the corners thereof. The lug 238 on the inner corner of the broad upper end projects rearwardly as well as upwardly and the lug 239 on the outer corner projects forwardly as well as upwardly.

The lugs 238 and 239 on the lever 82 are arranged to contact with an enlargement 240 formed on the lower end of an oscillatory mounted lever 241 carried on a spindle 242 that is supported in the sides of the clamping frame 54. The lever 241 projects above the spindle 242 and is provided with a weight 243. The spindle carrying the lever 241 is located on the inner side of the feed chutes and an arm 244 projects outwardly from the pivot point of said lever and rests upon the ends of arms 245 fitted to the inner ends of spindles 246 mounted in bearings 247 formed on the clamping frame 54.

The outer ends of the spindles 246 are

formed with depending arms 248 that are connected by a tension spring 249 and the central parts of said spindles are fitted with upwardly projecting arms 250 that are arranged centrally with the feed chutes 49 and 50 and normally are clear of the lid and body in the lower ends thereof.

The lug 239 on the outer corner of the broad end of the lever 82 is adapted to contact with the outer face of the enlargement 240 on the lever 241 when the push rods 51 have nearly completed their inward stroke and cause the upper end of the said lever 241 to be swung outwardly as hereinafter described. When the lever 241 is swung outwardly the arm 244 bears downwardly on the arms 245 thereby causing the spindles 246 to partially rotate and move the arms 250 away from the lid and body in the lower ends of the feed chutes. When the arms 250 are moved away from the lid and body in the lower ends of the feed chutes the said lid and body is free to fall on to the steps 65 when the push rods 51 have reached the limit of their inward stroke. The lever 241 and parts co-acting therewith are shown in their normal positions in Fig. 18 of the drawings. When the lever 241 is in its normal position the weight 243 overcomes the tension of the spring 249 and the lower end of the said lever is tilted inwardly slightly beyond the point reached by the lug 239 on the outer corner of the broad end of the lever 82 when the same is at the inner end of its travel, see dotted lines in Fig. 18.

When it is desired to cut off the feed of the lids and bodies in order to adjust the mechanism without passing said lids and bodies through the press, the spindle 242 is thrust rearwardly thereby placing the enlargement 240 on the lower end of the lever 241 in the path of movement of the lug 238. When the spindle 242 is in its normal position—as shown in Fig. 18—the enlargement 240 on the lower end of the lever 241 is in the path of movement of the lug 239 on the lever 82. The spindle 242 is retained in its forward and rearward positions by means of a locking pin 251 and grooves 252 formed circumferentially in said spindle. The paths of movement of the lugs 238 and 239 are indicated by curved dotted lines *a* and *b* respectively. When the upper end of the lever 82 is moved outwardly the lug 238 thereon strikes the inner face of the enlargement 240 on the lever 241 and tilts the weighted end of said lever inwardly. The tension spring 249 causes the spindles 246 to partially rotate in their bearings thereby moving the arms 250 outwardly into position to engage and support the lids and bodies in the chutes. When the lower end of the lever 241 is swung outwardly the enlargement 240 is carried slightly beyond

the points reached by the lug 238 when at the outer end of its travel. The front end of the spindle 242 is provided with a knob 253 for convenience of operation, and adjustable stops 254 are provided for limiting the swinging movement of said lever.

The lever 241 and parts co-acting therewith are returned to their normal positions to release the lids and bodies in the chutes.

10 It will be obvious that the lids and bodies to be hingedly connected by the dies must pass down the feed chutes with their open sides facing each other and with the side of the lids having the pintle margin uppermost.

In order to effect the correct feeding of the lids a slot 255 is made longitudinally in the top of and extending the full length of the chute 49 and said slot is sufficiently wide to accommodate the pintle margin on the backs of the lids and permit them to gravitate freely down said chute.

The lids 47 to be correctly fed to the dies must enter the chute 49 with the pintle margin projecting upwardly and with the side furnished with said pintle margin farthest from the entrance to said chute.

A step 256 is formed in the bottom of the chute 49 near the entrance thereto. When 30 the back of a lid is passed over said step it falls downwardly on to the bottom of the chute in which position it will be free to pass beneath a bridge 257 formed transversely across the chute in advance of the step 256. 35 The bridge 257 prevents a lid being introduced into the chute 49 in any way but that above described.

A longitudinally disposed slot 258 is formed in the bottom of the chute 49 near 40 the feed end and any foreign matter entering said chute will pass therethrough.

In Figs. 11 and 12 of the drawings a lid is shown in dotted lines at 259 passing correctly in the chute and a lid is shown at 45 260 passing in its correct position down the chute.

The chute 50 for the bodies is shown at the right hand side of Fig. 11 and portion of the said chute is shown broken away to 50 more clearly illustrate the construction of the same.

A slot 261 is made in the bottom of the chute 50 near the feed end thereof and connecting with the ends of said slot 261 are 55 gaps 262 that pass longitudinally toward the feed end of the said chute. The width of the slot 261 is less than one-half the width of a body 48.

When a body is fed bottom upward into 60 the chute 50 its forward edge falls through the slot 261 and its side edges fall into the gaps 262 and the whole of the body gravitates or is passed through the slot 261 by the next oncoming body as at 263 (See Fig. 11).

65 The tongue 264 formed by the piece of ma-

terial between the gaps 262 prevents a body falling through the slot 261 when fed correctly into the chute 50.

A slot 265 is made in the bottom of the chute 50 to permit of bodies falling therethrough when fed endwise into the same and portion of the side of said slot 265 is cut away at 266 to permit of a body falling therethrough should it turn and pass diagonally through the chute.

75 A plate 267 can be fitted to the underside of the chute 50 near the slot 261 to direct the bodies falling therethrough to any desired point.

A modified form of feed chute for the lids 80 is shown in sectional elevation in Fig. 45 of the drawings the lower end being shown broken off for convenience of illustration.

The entrance to the feed chute is flared to 85 permit of the free entrance of the lids and a slot 268 is formed in the bottom thereof for a suitable distance.

The chute is made large enough to permit of a lid being introduced in any position and the slot 268 is sufficiently wide to permit 90 of a lid passing therethrough should it be fed endwise into the chute. A recess 269 is formed at the side of the slot 268 to permit of a lid falling out of the chute should it be fed endwise therein and pass diagonally 95 therealong.

A slot 270 is cut longitudinally in the front side of the chute from a point where it curves downwardly to any suitable point and a slot 271 commencing at a lower point 100 is cut longitudinally in the back of the said chute.

The chute inclines forward slightly below the bottom of the slot 270 and from this point a branch chute 272 passes vertically 105 downward.

The chute is made sufficiently deep above the top of the slot 271 to permit the whole of a lid passing freely therethrough and below the top of said slot the chute is made 110 shallower so that the pintle margin on the back of the lid rim will be forced to slide in either of the slots 270 or 271 according as it is fed into the chute.

In order to direct the lids correctly down 115 the chute they are fed into the upper end thereof with the rim having the pintle margin projecting upwardly and rearwardly. The lids fed to the chute as above described slide freely down the same and the pintle margins strike against an inclined plate 273 that is located at the bottom of the slot 270 that causes the front edge of the lids to tilt 120 forwardly in line with the inclined portion of the chute.

125 The lid is suspended momentarily from the inclined plate 273 and then falls correctly down the chute. The back of the chute is formed with an outwardly projecting bulge 274 at a point opposite to the in-

clined plate thereby increasing the width sufficiently to permit the lids to fall freely from said inclined plate. When a lid is fed into the chute with the rim edge downward 5 it will fall straight down and enter the branch chute 272. The lower part of the chute is provided on its front with a longitudinal slot 275 that accommodates the pin-tle margins of the lid rims and permits them 10 to pass freely downward to the stepped platform 53 on the push rods 51.

The inclined plate 273 is fitted to lugs 276 formed on the front of the chute and the angle of said plate can be adjusted by means 15 of bolts 277 and slots 278 (see Fig. 45 of the drawings).

Fig. 48 of the drawings illustrates a modified form of lid controlling device for the third die 34' that has been devised in order 20 to obviate the use of the spring controlled arm 195. The free end of the arm 185 in this instance is designed to support a magnet 279 the pole of which is fitted to a lid holder 280 of non-magnetic material. The 25 magnet has just sufficient energy to hold the lid with a degree of tightness required during hinging operations. The magnet is energized by a coil 281 that receives its current through wires 282 connected to a battery 283. A permanent magnet, of ordinary 30 design, can be employed in lieu of the electro-magnet above described.

It will be obvious that the construction and arrangement of the parts of the machine can be modified to permit of the lids and bodies being fed into the left hand side of the machine and discharged from the right hand side thereof and that various slight and immaterial modifications can be 40 made therein without departing from the spirit and scope of the invention as hereinbefore described and as outlined in the following claiming clauses.

What I do claim is:—

45 1. An apparatus for forming hinge members on and connecting the lids and bodies of sheet metal receptacles, the combination with a frame, and a die carrying head mounted in the frame to have vertically reciprocating movement, of a base slidably mounted on the frame below the head carrying dies complementary to the dies carried by the head; means for securing the die base to the frame below the head; a driving 50 shaft mounted in the frame and operatively connected to the die carrying head to actuate the same; a horizontal shaft mounted on the side of the frame and operatively connected to the driving shaft; and means operative from the horizontal shaft to intermittently and progressively feed lids and bodies to the dies on the die base; said die base with the feeding means for the lids and bodies being movable from beneath the 55 die carrying head and the feeding means

for the lids and bodies maintained in operative connection with the horizontal shaft during such movement of the die base for the purpose specified.

2. An apparatus for forming hinge members on and connecting the lids and bodies of sheet metal receptacles, the combination with a frame, and a die carrying head mounted in the frame to have vertical reciprocatory movement, of a base slidably mounted on the frame below the head carrying dies complementary to the dies carried by the head; a lateral extension on the die base; gravity feed chutes for the lids and bodies fitted to the lateral extension; reciprocatingly mounted push-rods on the die base in front and at the rear of the dies on the die base having stepped platforms at the outer ends and located beneath the feed chutes; guides on opposite sides of the push-rods; spring pawls on said guides; means for pushing the lids and bodies onto and for removing them from the dies on the die base; means carried by the push-rods for conveying the lids and bodies intermittently and progressively from one die to another die on the base; and means to move the die base in position below the head and from beneath said head without disturbing the operative connection of the lid and body feeding means for the purpose specified.

3. An apparatus for forming hinge members on and connecting the lids and bodies of sheet metal receptacles, the combination with a frame, and a die carrying head reciprocatingly mounted in said frame, of a base mounted on the frame below the die carrying head and carrying dies complementary to the dies carried by the head; a driving shaft mounted in the frame operatively connected to the die carrying head to actuate the same; a horizontal shaft mounted at the rear of the die base and operatively connected to the driving shaft; a cam on the horizontal shaft; a lever pivoted on the rear of the die base carrying a roller to bear against the cam; a lever pivotally mounted on the front of the die base; a rod having one end pivoted to the lever at the rear of the die base and its opposite end adjustably and resiliently connected to the lever at the front of the die base; bars reciprocatingly mounted on top of the die base at the front and rear of the dies connected to and operative from the levers; push-pads resiliently mounted in the reciprocatingly mounted bars opposite the bottom dies; and ejector arms fitted adjustably to said bars.

4. In an apparatus for forming hinge members on and connecting the lids and bodies of sheet metal receptacles, a frame; a die-carrying base on the frame; a horizontal shaft on the rear of the die base oper-

atively connected to driving means; a cam on the horizontal shaft; a lever pivoted on the rear of the die base carrying a cam following roller at one end to bear against the 5 cam; a lever pivotally mounted on the front of the die base operatively connected to the first lever, whereby as movement is imparted by the cam to said first lever movement will be imparted to the other lever in an oppo- 10 site direction; bars reciprocatingly mounted on top of the die base at the front and rear of the dies and connected to and operative from the levers; push-pads resiliently mounted in the bars opposite the dies on the 15 die base to move the lids and bodies onto the dies, during the forward movement of the bars; and arms adjustably secured to said bars to eject the lids and bodies from the dies during the return movement of the bars.

20 5. An apparatus for forming hinge members on and connecting the lids and bodies of sheet metal receptacles, comprising a frame; a die carrying head reciprocatingly mounted in the frame; a die carrying base 25 mounted on the frame below the head; a driving shaft on the frame operatively connected to the die carrying head to actuate the same; a horizontal shaft mounted on the side of the frame operatively connected to 30 the driving shaft; a cam on the horizontal shaft; a lever pivoted to the side of the die base carrying a cam following roller at one end to bear against the cam; a spring connection between the lever and the die 35 base; an adjustable stop for the lever; push-rods reciprocatingly mounted in the top of the die base at the front and rear of the dies on the base; and a link connecting the outer ends of the push-rods to the upper end of 40 the lever.

45 6. In an apparatus for forming hinge members on and connecting the lids and bodies of receptacles, a frame; a driving shaft; a die carrying base mounted on the frame; a horizontal shaft mounted on the side of the frame and driven by the driving shaft; a cam on said shaft; a lever pivotally supported by the die base having a cam following roller at one end to coöperate with 50 the cam; push-rods connected to the free end of the lever reciprocatingly mounted in the top of the die base, one at the front and the other at the rear of the dies, arranged to support the lids and successively advance 55 them to the dies.

60 7. In an apparatus for forming hinge members on and connecting the lids and bodies of sheet metal receptacles, a reciprocating head and a die base, three sets of dies the top dies of which are carried by the head and the bottom dies by the base, hinge forming members on the faces of the first and second sets of dies, means on the third set of dies for connecting the hinge members

of the lid and body formed by the preceding 65 two sets of dies, a guide-way extending along the front of the three bottom dies, a guide-way extending along the rear of the first and second bottom dies, push-rods, fingers on the push-rods projecting into the 70 guide-ways and simultaneously conveying lids and bodies intermittently from one set of dies to another, a reciprocatingly mounted push-pad in front of each of the three bottom dies, a reciprocatingly mounted 75 push-pad at the back of each of the first and second bottom dies, reciprocatingly mounted ejector rods for removing the bodies from the front of each of the three bottom dies, reciprocatingly mounted ejector rods for removing the lids from the back of each of the first and second bottom dies, a curved arm pivoted at one end beneath the third bottom die, a lid-holder fitted to the opposite end of the curved arm and normally in alinement 80 with the guide-way at the rear of the bottom dies, a roller on the curved arm, a shaft mounted at the rear of the die-base, a cam on the shaft and bearing against the roller, an extension on the curved arm, a vertical rod 85 pivoted to the extension and reciprocatingly mounted at the rear of the third bottom die, a spring connecting the curved arm to the die-base, and means for frictionally retaining 90 a lid within the lid-holder.

95 8. In an apparatus for automatically forming hinge members on and connecting the lids and bodies of sheet metal receptacles, a frame; a die carrying base mounted on the frame; a driving shaft; a horizontal shaft on the side of the frame driven from the driving shaft; a cam on the horizontal shaft; a lever pivoted to the side of the die base; a roller carried by the lever to engage the cam; a spring connected to the lever to 105 maintain the roller in engagement with the cam; an adjustable stop for the lever; push-rods reciprocatingly mounted in the die base at the front and rear of the dies carried thereby arranged to support the lids and 110 bodies and successively advance the same to the dies; and means to connect the push-rods to the lever to impart reciprocatory movement thereto through the movement of the lever.

115 9. In an apparatus for automatically forming hinge members on and connecting the lids and bodies of sheet metal receptacles, a frame; a reciprocatingly mounted die carrying head; a die carrying base 120 mounted on the frame below said head; reciprocating carriers at the front and rear of the dies for the lids and bodies to successively advance the same to the dies; a to and fro movable lever to reciprocate the carriers; a guide frame on one end of the die base; gravity chutes for the lids and bodies the ends of which are connected to the 125

guide frame to guide the lids and bodies to the carriers; longitudinal slots in the opposite faces of the feed chutes; a pivoted lever having a weight at one end and an enlargement at the other end; an arm projecting laterally from the lever; pivotally supported arms having their free ends located beneath the lever arm; arms depending from the support of the first arms; adjustable stops for the weighted lever; and lugs on the to and fro movable lever to engage with the enlargement of the weighted lever to operate said lever for the purpose specified.

10. In an apparatus for automatically forming hinge members on and connecting the lids and bodies of sheet metal receptacles, a frame, a reciprocatingly mounted die-carrying head, a die-base mounted on the frame, three top dies secured to the die-carrying head and three bottom dies secured to blocks mounted on the die-base, a recess in the front and in the back of each of the die-blocks, a depressible platform beneath the back and a depressible platform beneath the front of each of the first and second bottom dies, a rod mounted vertically in and having its upper end projecting through the top of the die-base, a resilient member exerting an upward pressure on the rod, a cross-head 25 on the rod, shanks depending from the platforms and secured to the cross-head, and an adjustable rod depending from the underside of the die-carrying head.

11. In an apparatus for automatically forming hinge members on and connecting the lids and bodies of receptacles, a frame; a die carrying base; gravity feed chutes for the lids and bodies; a guide frame at one end of the die base to which the chutes are secured; push-rods reciprocatingly mounted at the front and rear of the dies; stepped platforms on the push-rods adjacent the guide frame; fingers on the push-rods forwardly of said platforms; guides on the sides of the push-rods between the guide frame and the first die; and spring pawls on the sides of the guides.

12. In an apparatus for automatically forming hinge members on and connecting the lids and bodies of sheet metal receptacles, a die-base, a die-block fitted to the base having a vertical front side and an inclined rear side, a die fitted to the block, an arm pivoted at one end beneath the die block, a lid-holder fitted to the opposite end of the arm, a roller on the arm, a cam bearing against the roller, and a vertically movable rod pivoted to the arm and reciprocatingly mounted in the die-block.

13. In an apparatus for automatically forming hinge members on and connecting the lids and bodies of sheet metal receptacles, a die-base, a die-block fitted to the die-base, a die fitted to the block, an arm

pivoted at one end beneath the die-block, a 65 boss on the opposite end of the pivoted arm, a lid-holder, a stem on the lid-holder fitted resiliently in the boss, a flange on the upper edge and a flange on the lower edge of the lid-holder, a roller on the pivoted arm, a 70 shaft mounted on the die-base, and a cam on the shaft bearing against the roller.

14. In an apparatus for automatically forming hinge members on and connecting the lids and bodies of sheet metal receptacles, 75 a die-base, a die-block on the die-base, a die fitted to the die-block, an arm pivoted at one end beneath the die-block, a lid-holder on the opposite end of the arm, a roller on the arm, a horizontal shaft at the rear of the 80 die-base, a cam on the shaft, a roller on the pivoted arm and bearing against the cam, and an adjustable stop for the pivoted arm.

15. In an apparatus for automatically forming hinge members on and connecting 85 the lids and bodies of sheet metal receptacles, a die-base, a die-block on the die-base, a die on the die-block, an arm pivoted at one end beneath the die-block, a lid-holder fitted to the opposite end of the arm and means 90 for oscillating said arm.

16. In an apparatus for automatically forming hinge members on and connecting the lids and bodies of sheet metal receptacles, a die-base, a die-block on the die-base, 95 a die on the die-block, an arm pivoted at one end beneath the die-block, a lid-holder on the opposite end of the pivoted arm, an extension on the pivoted arm, a rod pivoted at its lower end to the extension, and reciprocatingly mounted at its upper end in the die-block, a second arm pivoted in axial alinement with the arm fitted with the lid-holder and having its upper end located between the lid-holder and the die-block, and 100 a cross-piece on the upper end of the second pivoted arm.

17. In an apparatus for automatically forming hinge members on and connecting the lids and bodies of sheet metal receptacles, 110 a die-base, a die-block on the die-base, a die on the die-block, an arm pivoted to the die-base beneath the die-block, a lid-holder on the pivoted arm, a vertical rod reciprocatingly mounted in the rear of the die-block, a second arm pivoted in axial alinement with the arm fitted with the lid-holder and having its upper end located between the lid-holder and the die-block, a cross-piece on the upper end of the second pivoted 115 arm, and stops for determining the normal positions of the two pivoted arms.

18. In an apparatus for automatically forming hinge members on and connecting the lids and bodies of sheet metal receptacles, 125 a die-base, a die-block on the die-base, a die on the die-block, an arm pivoted to the die-base beneath the die-block, a lid-holder

- on the pivoted arm, a vertical rod reciprocatingly mounted in the rear of the die-block, a second arm pivoted in axial alignment with the arm fitted with the lid-holder 5 and having its upper end located between the lid-holder and the die-block, a cross-piece on the upper end of the second pivoted arm, stops for determining the normal positions of the two pivoted arms, a lug depending from the pivot point of the second arm, 10 a spring exerting a rearward pressure on the second arm, and a spring exerting a rearward pressure on the arm carrying the lid-holder.
- 15 19. In an apparatus for automatically forming hinge members on and connecting the lids and bodies of sheet metal receptacles, a die-base, a die-block on the die-base, a die on the die-block, an arm pivoted to the 20 die-base beneath the die-block, a lid-holder on the pivoted arm, a vertical rod reciprocatingly mounted in the rear of the die-block, a second arm pivoted in axial alignment with the arm fitted with the lid-holder 25 and having its upper end located between the lid-holder and the die-block, a cross-piece on the upper end of the second pivoted arm, stops for determining the normal positions of the two pivoted arms, a lug depending from the pivot point of the second arm, 30 a spring exerting a rearward pressure on the second arm, a spring exerting a rearward pressure on the arm carrying the lid-holder, guide plates fitted to the die-base—one on 35 each side of the die-block, recesses in the inner faces of the guide plates, and an inclined bracket on one of the guide plates.
- 20 20. In an apparatus for automatically forming hinge members on and connecting 40 the lids and bodies of sheet metal receptacles, a die-base, die-blocks on the die-base, die members on the die-block, recesses in the sides of the die-blocks, reciprocatingly mounted curved ejector arms, and cross-pieces on the ends of the ejector arms fitted 45 slidably in the recesses in the die-blocks.
21. In an apparatus for automatically forming hinge members on and connecting the lids and bodies of sheet metal receptacles, 50 a frame, a die-base slidably mounted on the frame, a horizontal shaft mounted revolubly on the side of the frame, a horizontal shaft mounted transversely on the rear of the die-base, a gear wheel on the transverse shaft, a gear wheel fitted slidably on and rotating with the shaft on the side of the frame and meshing with the gear wheel on the transverse shaft, a sleeve on the gear wheel on the shaft located at the 55 side of the frame, collars on the sleeve, a bearing on the slidably mounted die-base engaging the sleeve between the collars thereon, a driving-shaft on the frame, and a counter-shaft and gearing operatively connecting the driving-shaft to the horizontal 60 shafts.
22. In an apparatus for automatically forming hinge members on and connecting the lids and bodies of sheet metal receptacles, a frame, a die-base slidably mounted on the 65 frame, a horizontal shaft on the side of the frame, a transverse shaft on the rear of the die-base, a gear wheel on the transverse shaft, a gear wheel fitted slidably on and rotating with the horizontal shaft and 70 meshing with the gear wheel on the transverse shaft, a sleeve on the gear wheel on the horizontal shaft, collars on the sleeve, a bearing on the slidably mounted die-base engaging the sleeve between the collars 75 thereon, a driving-shaft on the frame, a counter-shaft and gearing operatively connecting the driving-shaft to the horizontal shaft, a shaft passing transversely through the frame, a pinion on the shaft mounted 80 transversely in the frame, a handle on the shaft passing through the frame, slots in the bottom of the die-base, and bolts fitted in the frame and passing through the slots in 85 the die-base. 90
23. In an apparatus for automatically forming hinge members on and connecting the lids and bodies of sheet metal receptacles, the combination with a frame, and a reciprocable die carrying head, of a die-base 95 mounted on the frame, die-blocks mounted on the die-base, recesses in the front and in the back of the die-blocks, and a de-pressible platform beneath the back and a de-pressible platform beneath the front of each 100 of the die-blocks for the purpose specified. 100
24. In an apparatus for automatically forming hinge members on and connecting the lids and bodies of sheet metal receptacles, the combination with a reciprocable die 105 carrying head, of a die-base, a die-block fitted to the die-base having a vertical front side and an inclined rear side, a die fitted to the block, an arm pivoted at one end beneath the die-block, and a lid-holder fitted to the 110 opposite end of the arm for the purpose specified. 110
25. In an apparatus for automatically forming hinge members on and connecting the lids and bodies of sheet metal receptacles, 115 the combination with a frame, of a reciprocable head carrying a plurality of dies, a die-base on the frame, a plurality of bottom dies on the die-base, complementary to the dies carried by the head, a horizontal shaft 120 on the side of the frame, a cam on the horizontal shaft, a lever pivoted to the side of the die-base, a roller on the lever bearing against the cam, an adjustable stop for the lever, push-rods reciprocatingly mounted on 125 the die-base—one at the front and the other at the rear of the bottom dies, screwed extensions on the outer ends of the push-rods, 125

- a cross-piece connecting the screwed extensions, adjustment nuts on the screwed extensions, and a link connecting the cross-piece to the lever pivoted to the side of the die-base. 5
26. In an apparatus for automatically forming hinge members on and connecting the lids and bodies of sheet metal receptacles, the combination with a frame, and a die 10 carrying head mounted in the frame to have vertical reciprocating movement, of a base mounted on the frame below the die carrying head carrying dies complementary to the dies carried by the head, a shaft revoluble 15 on a horizontal axis on the side of the frame, a cam on the horizontal shaft, a lever pivoted to the die-base, a roller on the lever bearing against the cam, push-rods reciprocatingly mounted in the top of the die-base 20 at the front and rear of the bottom dies, a guide frame on one end of the die-base in line with the push-rods, a clamping frame on the guide frame, gravity feed chutes for lids and bodies secured to the guide frame 25 by the clamping frame, slots formed in the opposite faces of the feed chutes, a spindle slidably mounted in the clamping frame, a lever pivotally supported on the spindle, a weight on the upper end and an enlargement 30 on the lower end of the lever, an arm on the lever, spindles passing transversely through the clamping frame, arms on the inner ends of the spindles and having their ends located beneath the arm on the lever, 35 arms depending from the outer ends of the spindles, a tension spring connecting the depending arms, arms projecting upwardly from the centers of the transversely disposed spindles, adjustable stops for the 40 weighted lever, and lugs on the upper end of the lever pivoted to the side of the die-base for the purpose specified. 45
27. In an apparatus for forming hinge members on and connecting the lids and bodies of sheet metal receptacles, a frame, a die carrying head reciprocatingly mounted in the frame, a die carrying base mounted in the frame below said head; reciprocable carriers at the front and rear of the dies 50 on the base for the lids and bodies to successively advance the same to the dies, a to and fro movable lever to reciprocate the carriers, a guide frame on one end of the die base, gravity feed chutes for the lids and 55 bodies connected at the lower ends to the guide frame to guide the lids and bodies to the carriers, and means operable by the lever during the lid and body advancing movement of the carriers to prevent the discharge 60 of the lids and bodies from the chutes. 65
28. In apparatus for forming hinge members on and connecting the lids and bodies of receptacles, the combination of a frame; a reciprocatory head carrying three sets of 70 dies; a die base carrying three bottom dies secured to blocks mounted on the base; yieldingly compressible platforms beneath the front and back of the first and second bottom dies; and means carried by the reciprocatory die head operable to depress said 75 platforms during the descending movement of said die head for the purpose specified. 80
29. In apparatus for forming hinge members on and connecting the lids and bodies of sheet metal receptacles, the combination of a die carrying base; gravity feed chutes for the lids and bodies; a guide frame at the end of the die base to which the chutes are connected; reciprocating push rods mounted at the front and rear of the dies 85 having stepped platforms at the ends adjacent the guide frame and fingers forwardly of said platforms; guides at the sides of the push rods between the guide frame and first die; and yielding fingers carried by said 90 guides for the purpose specified. 95
30. In apparatus for forming hinge members on and connecting the lids and bodies of receptacles, the combination with a reciprocable head and a base, of complementary die members carried thereby to form hinge members on the lids and bodies of the receptacles; a die carrying block on the base having a vertical front side and an inclined rear side; a pivoted lid holder carrying arm operable to move and hold a lid on the inclined rear side of the die block; and a rod to have vertical reciprocating movement in an opening in the die block through the movement of the arm and operable to move 100 the lid from the die block as the arm moves to position to release the lid holder carried thereby from the lid for the purpose specified. 105
31. In apparatus for forming hinge members on and connecting the lids and bodies of receptacles, the combination with a reciprocable head and a die base, of complementary die members carried thereby to form hinge members on the lids and bodies of the receptacles; a die carrying block on the base; a pivoted cam actuated arm; a lid holder yieldingly carried by said arm; and a rod to have vertical reciprocating movement in the die block operable by the lid holder carrying arm to withdraw said rod from the opening when the arm moves to lid holding position toward the die block and to move said rod through said opening and release the lid from the die block as the lid holder 110 carrying arm moves to lid releasing position for the purpose specified. 115
32. In apparatus for forming hinge members on and connecting the lids and bodies of receptacles, the combination with a reciprocable head and a die base, of complementary die members carried thereby to form hinge members on the lids and bodies of the 120

receptacles; a die carrying block on the base; a pivoted two-armed lever; a lid holder yieldingly carried by said lever; means to move said lever and the lid holder 5 toward and away from the die block; means carried by the lever to yieldingly hold a lid in the lid holder during the movement of the lever toward the die block; a rod carried by the lever to have reciprocatory movement in an opening in the block, said rod 10 being withdrawn from the opening during the movement of the lever to move the lid holder toward the die and moved up through said opening to release a lid from the die 15 block during the movement of the lever to move the lid holder to lid releasing position for the purpose specified.

33. In apparatus for forming hinge members on and connecting the lids and bodies 20 of receptacles, the combination with a reciprocable die carrying head and a base, of blocks on the base carrying dies complementary to the dies carried by the head; means to move the lids and bodies onto said blocks; 25 recesses in the blocks; and reciprocable ejector arms having a part to slidably engage in the block recesses to engage with and

operable to move the lids and bodies from the blocks for the purpose specified.

34. In apparatus for forming hinge members on and connecting the lids and bodies of receptacles, the combination with a reciprocable die carrying head and a base, 30 of blocks mounted on the base carrying dies complementary to the dies carried by the head; depressible platforms along which the lids and bodies are moved to the respective dies on the blocks; means to move the lids and bodies onto the die blocks; means to depress the platforms as the lids and bodies 35 are moved onto the die blocks; recesses on the inner sides of the die blocks; and reciprocable ejector arms having a part to engage in the block recesses to engage with and 40 operable to move the lids and bodies from the blocks for the purpose specified.

In testimony whereof I affix my signature in presence of two witnesses.

GEO. W. BERRY.
